(57) **CLAIM**

The ornamental design for a lugged cap assembly, as shown and described.

DESCRIPTION

FIG. 1 is a front plan view of a lugged cap assembly design wherein the opposite back side view is a mirror image thereof;

FIG. 2 is a top plan view of FIG. 1;

FIG. 3 is a right side plan view of the lugged cap assembly of FIG. 1 rotated 90° wherein the opposite left side view is a mirror image thereof; and,

FIG. 4 is a front perspective view of the lugged cap assembly of FIG. 1.

The broken lines showing the canister and lugged cap assembly in FIGS. 1-4 are for illustrative purposes only and form no part of the claimed design.
